UNITED STATES PATENT OFFICE.

WILLIAM C. RASTETTER, OF FORT WAYNE, INDIANA.

DESIGN FOR A FOLDING CHAIR.

Application filed January 28, 1925. Serial No. 12,174. Term of patent 14 years.

To all whom it may concern:

Be it known that I, WILLIAM C. RASTETTER, a citizen of the United States, residing at Fort Wayne, in the county of Allen and State of Indiana, have invented a new, original, and ornamental Design for a Folding Chair, of which the following is a specification, reference being had to the accompanying drawing, forming part thereof.

The figure is a perspective view of a folding chair showing my new design.

I claim the ornamental design for a folding chair as shown.

WILLIAM C. RASTETTER.

Witnesses:

K. SCHERZINGER,
MATILDA METTLER.
